UNITED STATES PATENT OFFICE.

CHARLES ROSIER, OF NEW YORK, N. Y.

TIE-SLIP.

1,399,579.

Specification of Letters Patent.

Patented Dec. 6, 1921.

Application filed June 26, 1920. Serial No. 391,893.

To all whom it may concern:

Be it known that I, CHARLES ROSIER, a citizen of the Republic of France, residing at New York, in the county of New York and State of New York, have invented certain new and useful Improvements in Tie-Slips, of which the following is a specification.

This invention relates to a tie slip for removable application to collars, and the primary object of the same is to provide a simple device particularly constructed for easy insertion in the back portion of a collar and engagement with an adjacent collar button to effect a free slipping movement of a necktie between the folded portions of a collar to facilitate the formation and proper disposition of the tie knot, and a subsequent ready detachment and removal without displacement of the applied and knotted tie.

The invention consists in the construction and arrangement of parts more fully herein-after described and claimed in preferred form.

25 In the drawing:—

Figure 1 is a perspective view of a collar showing the improved device applied thereto.

Fig. 2 is a horizontal section through a 30 part of the rear portion of a collar, neck-band of a shirt and the improved device.

Fig. 3 is a transverse vertical section taken through the center of the rear portion of a collar, neck-band of a shirt and the improved device.

Fig. 4 is a detail perspective view of the improved slip device.

The improved device consists of a longitudinally curved body 5 having the opposite ends formed with inturned flanges 6 and the center of the lower edge provided with a concave recess 7. The body 5 will be preferably wider than folds of the collar with which it is used. The longitudinally curved 45 contour of the body produces an outer convex side 8 and conversely an inner concave side 9 to respectively conform to the outer and inner folds 10 and 11 of the collar. The inner fold of the collar as usual rests against 50 the neckband 12^a, as shown by Figs. 2 and 3. The inner concave side 9 of the body 5 conjointly with the end flanges 6 provides a recessed side when the said flanges bear on the outer surface of the inner collar fold 11, 55 and extending centrally and vertically over said inner recessed side of the body is a com-

bined flexible operating strap and grip 12 secured at its upper end 13 to the top portion of the recessed side. The remaining portion of the strap and grip 12 is loose and depends 60 below the lower edge of the body and over the recess 7 which serves to expose a considerable length of the strap and grip and also to permit the finger of the hand to be applied well up on the strap and grip. The 65 strap and grip 12 close to its upper secured end 13 is formed with an opening 14, and from the lower central portion of this opening a slot 15 extends downwardly for a distance in the strap and grip. The body 5 is of 70 greater width than the width of the folds 10 and 11 of the collar to expose a portion of the body below the lower edges of the collar folds when the device is applied to render the placement and removal of the device 75 more convenient and positive.

The preferred material used in forming the improved device will be celluloid, which may be readily shaped as specified, and colored if desired. It will be understood, 80 however, that any other material adapted for the purpose may be used.

In the use of the device the tie is first inserted between the folds 10 and 11 of the collar and the improved device is then applied by inserting the body 5 between the inner side of the tie and the outer surface of the inner collar fold 11 with the opening 14 opposite the back button hole 16 in the said fold and the back button 17 which is caused 90 to engage said hole. The back button head is next pushed through the opening 14 and by means of the combined strap and grip 12 the device as an entirety is pushed upwardly and the button shank caused to enter the 95 slot 15, which, being narrower than the diameter of the back button head, will temporarily hold the improved device in place. The tie may then be readily drawn and will easily slip around between the collar folds 100 as it bears on the rear convex side of the body 5, and after proper adjustment the tie knot is formed and properly disposed at the front of the collar. The user then pulls downwardly on the strap and grip 12 until 105 the button shank clears the slot 15 and the button head is opposite the opening 14 when the device may be readily released by pulling rearwardly thereon and withdrawn from between the collar folds 10 and 11 by a further downward pull thereon without affecting or displacing the secured tie.

The end flanges 6 of the body 5 closely bear on the inner collar fold 11 when the device is in use and preserve the recess formation at the inner side of the body to compensate for the added thickness of the combined strap and grip 12 to avoid binding action relatively to the collar folds and also to assist in holding the improved device in place when applied.

10 The improved device will be advantageous in readily applying and tying neckties, and being simple in construction may be cheaply manufactured.

What is claimed is:—

15 1. A tie slip of the class specified for removable insertion between the folds of a collar, consisting of a body with a concave recessed side, and a combined operating strap and grip partially secured to and 20 extending over said recessed side and depending below the lower edge thereof, the said strap and grip having a slot for removable engagement of a button therewith.

2. A tie slip of the class specified for removable insertion between the folds of a collar, consisting of a body having a concave recessed side and an operating strap partially secured to said recessed side and having its greater portion loosely and 30 centrally extending over one side and depending below the lower edge thereof.

3. A tie slip of the class specified for removable insertion between the folds of a collar, consisting of a body having an operating strap secured to and extending over one side and depending below the lower edge thereof, the opposite ends of the body having inwardly projecting flanges.

4. A tie slip of the class specified for removable insertion between the folds of a collar, consisting of a longitudinally curved body with a concave recessed side, and a button-engaging strap partially secured to said recessed side and extending over the

latter side and depending below the lower 45 edge of the body for exposure below the lower edges of the collar folds, the greater portion of the slip being held out of contact with the rear side of the inner collar fold when applied to a collar. 50

5. A tie slip of the class specified for removable insertion between the folds of a collar, consisting of a longitudinally curved body having inwardly projecting end flanges, and a button engaging strap secured to and extending over one side and depending below the lower edge thereof. 55

6. A tie slip of the class specified for removable insertion between the folds of a collar, consisting of a longitudinally curved body having inwardly projecting end flanges to provide an inner concave side and an outer convex side, the said flanges co-operating to give the inner side of the body a recessed form, and a button engaging strap 65 partially secured to and extending over said inner concave side of the body and depending below the lower edge of the latter.

7. A tie slip of the class specified for removable insertion between the folds of a collar, consisting of a longitudinally curved body having inwardly projecting end flanges to provide an inner concave side and an outer convex side, the said flanges co-operating to give the inner side of the body 75 a recessed form, and an operating strap having a button engaging opening and slot therein and partially secured to and extending over said inner concave side of the body and depending below the lower edge of the 80 body.

In testimony whereof I have hereunto set my hand in presence of two subscribing witnesses.

CHARLES ROSIER.
